GLOBE HOLDER

Filed July 15, 1930

UNITED STATES PATENT OFFICE

PAUL J. PFEIFER, OF CLEVELAND HEIGHTS, OHIO, ASSIGNOR TO THE JOHN C. VIRDEN COMPANY, OF CLEVELAND, OHIO, A CORPORATION OF OHIO

GLOBE HOLDER

Application filed July 15, 1930. Serial No. 468,002.

This invention relates to globe holders, and more particularly to means carried by devices of this character for detachably retaining globes and the like.

5 It is an object of the present invention to provide a spring biased retaining device which is constructed and arranged to operate with a minimum flexing of the spring, whereby crystallization or fatigue of the 10 metal is avoided, and the life of the spring prolonged.

A further object of the invention is to provide a recess to receive the retaining device in inoperative position, to increase the clearance for installing the globe or the like.

Other objects and features of novelty will be apparent as the following description proceeds, reference being had to the accompanying drawings in which:

20 Fig. 1 is an elevation of a globe holder according to the preferred embodiment of the present invention, showing a portion of the globe, and parts of the view being broken away to show internal construction;

25 Fig. 2 is an inverted plan view of the structure shown in Fig. 1;

Fig. 3 is an elevation of a portion of the globe holder adjacent the latching mechanism;

30 Fig. 4 is a view of a portion of the structure shown in Fig. 2, showing the parts in latched position; and

Fig. 5 is an exploded view of movable parts of the latching mechanism as removed 35 from the holder.

Referring more particularly to the drawings, the globe holder 10 may be of any desired construction or shape, preferably a cup-shaped sheet metal member formed by stamping or spinning a flat sheet to form a pleasing contour. The sheet metal is preferably brass but obviously other metals may be used for this purpose. The top of the holder 10 may be provided with supporting and wiring apertures 11 and 12, and the lower portion of the inverted cup is provided with a flat, radial flange 13 and a depending annular flange 14 terminating in a rolled rim or bead 15.

50 The globe holder is adapted to support a

globe 16 which is provided with a flange or bead 17. Accordingly, the globe holder is provided with spaced abutment members 18 and a latching mechanism 19. The globe is inserted in the globe holder with the portion 55 17 in abutting relation with the abutments 18 and the latching mechanism 19 operated to engage the other side of the portion 17 and thus hold the globe in the globe holder.

The abutments 18 are preferably strips of 60 sheet metal, such as brass or other metals which are inherently pliable, or are annealed for this purpose. The strip of sheet metal is rolled or bent as at 20 to form the desired abutment, and secured inside the holder 10, 65 as by rivets 9. This construction is of advantage in that the abutment 18 may be manually varied. The roll 20 may be gripped by pliers and permanently compressed, to thus provide a larger opening to receive the portion 70 17, or the roll may be spread or bent inward to decrease the opening. The portions 17 may vary considerably in diameter for globes of approximately the same size, and this expedient affords a very simple means 75 for taking care of this variation.

The latching mechanism 19 includes a spring 21 which is secured inside the globe holder by means of a rivet 22. The spring 21 terminates in a notched end 23 which lies 80 within the corner 24 formed by the flanges 13 and 14. Interposed between the end 23 and the corner 24 is a retaining member 25, best shown in Fig. 5, as comprising a rigid member having a depending arm 26 and a shorter 85 lateral arm 27. The portion 27 is adapted to lie between the end 23 and the flange 13, with the portion 26 depending adjacent the flange 14. The corner 28 of the member 25 fits in the notch of the end 23 and the spring 21 90 urges the corner 28 into the corner 24.

The flange 14 is preferably pressed outwardly to form an inwardly facing recess 29 above the bead 15. A slot 30 extends transversely of the portion 29 just above the bead 95 15 and is adapted to receive an operating member 31, best shown in Fig. 5. The member 31 comprises a head or cam portion 32 which is adapted to lie between the depending portion 26 of the retaining member 25 and the 100

inner wall of the flange 14 at the pocket 29. The member 31 also comprises an extension 33 which is of reduced width, forming shoulders 34. This extension is passed through 5 the slot 30, so that the shoulders 34 rest against the flange 14 within the pocket 29 and above the bead 15, thus forming a pivotal mounting for the operating member 31.

In operation, assuming that a rough adjustment of the rolled portions 20 has been made to suit the globe portion 17 of the globe being installed, the operating arm 33 will extend radially through the flange 14, and thus the portion 32 will lie within the pocket 29 10 under the depending portion 26 of the operating member 25, which will also be housed within the pocket 29. This arrangement permits the latching mechanism to clear the globe bead 17 as the same is inserted into the 15 flange 14. The operating arm 33 will then move upwardly, causing the cam portion 32 to move inwardly and cam the depending portion 26 of the retaining member 28 into engagement with the outside of the globe bead 20 17. When the arm 33 completes its movement and lies snugly against the outside of the flange 14, the cam portion 32 has passed a dead center, and thus the latching mechanism has a snap action which holds it in 25 30 latched position. The inward movement of the portion 26 causes a downward movement of the corner 28 and consequent downward movement of the spring end 23. This arrangement is important as it will be noted 35 that the total movement of the spring end 23 is much less than the total movement of the lower end of the portion 26. The provision of adequate latching action with a very small movement of the portion 13 and consequent 40 slight flexing of the spring 21 serves to prolong the life of the spring inasmuch as the liability of crystallization or fatigue of the metal of the spring is reduced to a minimum.

While one embodiment of the invention has 45 been illustrated and described in such detail as to enable any one skilled in the art to practice the invention, nevertheless it is to be understood that the invention is not to be limited to the details disclosed, other than 50 as necessitated by the development of the prior art; but, instead, the invention embraces such embodiments of the broad idea as fall within the scope of the appended claims, it being obvious that various changes 55 may be made in the disclosed embodiment without departing from the spirit of the invention.

Having thus described my invention, I claim:

60 1. In a device of the class described, a holder, a lever spring fixed at one end to said holder, a retaining member biased by said spring and held on said holder by said spring, and means for moving said retaining member 65 against the action of said spring.

2. In a device of the class described, a holder, a spring carried by said holder, a pivoted retaining member biased by said spring and normally held in non-retaining position thereby, and a snap action member for moving and locking said retaining member in a retaining position against the action of said spring.

3. In a device of the class described, a holder, a spring carried by said holder, a retaining member having a portion held between said holder and spring and a depending portion, and a pivoted snap action member for moving said depending portion inwardly and locking it against the action of 75 said spring.

4. In a device of the class described, a holder, a retaining member mounted for pivotal movement with respect to said holder, said retaining member having arms of unequal length, and a spring secured to said holder and having the free end thereof engaging the shorter arm of said retaining member, whereby a limited flexing of said spring is caused by movement of said retaining member, said longer arm of the retaining member serving as the retaining arm.

5. In a device of the class described, a holder having an inwardly facing angular recess, angular latching means pivotally mounted in the angle of said recess and adapted when in the unlatched position to stand with its angular portions substantially parallel to the sides of said recess, and means pivotally mounted on said holder and having an external operating handle for controlling 85 90 said latching means.

6. In a device of the class described, a holder having a corner formed therein, a retaining member having a corner and a spring secured to said holder and having the free end thereof normally holding the corner of said retaining member in the corner of said holder, and means operated from the exterior of said holder for moving said retaining member against the action of said spring.

7. In a device of the class described, a holder, a spring secured inside said holder, a retaining member having a portion between said spring and holder and a depending portion, and an operating member having a cam portion between said retaining member and the holder and a finger piece projecting through a slot in said holder and adapted to be moved upwardly to be close against said holder, and said cam portion being adapted to cam said depending portion of said retaining member inwardly in response to such movement.

In testimony whereof, I hereunto affix my 125 signature.

PAUL J. PFEIFER.
